UNITED STATES PATENT OFFICE.

JACOB HENRY BECKMAN, OF OAKLAND, CALIFORNIA.

WATER HEATER.

Application filed March 9, 1921. Serial No. 450,837.

To all whom it may concern:

Be it known that I, JACOB HENRY BECKMAN, a citizen of the United States, residing at Oakland, in the county of Alameda and State of California, have invented new and useful Improvements in Water Heaters, of which the following is a specification.

This invention relates to a water heater, and particularly pertains to a heating unit 10 and electric heating means therefor.

It is the principal object of the present invention to provide a water heater adapted to be readily constructed to form separate heating units and to be readily heated by 15 self-contained electric heating means.

The present invention contemplates the use of a radiator, through which water is circulating, said circulation being maintained by electric heating means contained within 20 the unit, the heating element of said means being sectionized so that a decided degree of heat may be established and maintained within the radiator.

The invention is illustrated by way of example in the accompanying drawings, in which:

Figure 1 is a view in elevation showing the complete heater with parts broken away to more clearly disclose one of the heating 30 element sections.

Fig. 2 is a view in end elevation, showing the assembled heater.

Fig. 3 is an enlarged view in section and elevation showing one of the heating elements, and particularly disclosing the core construction.

Figure 4 is a central transverse sectional view of the heating element illustrated in Figure 3.

Referring more particularly to the drawings, 10 indicates a water radiator. This radiator is of common construction, being formed with a plurality of sections 11 intercommunicating at top and bottom. The 45 radiator is filled with water which circulates through the sections thereof, without leaving the heater except when excessive internal pressures are produced, at which time the steam may blow off through a safety valve 12.

A circulating pipe 13 is secured to the upper end of the radiator and extends downwardly to communicate with a heat dome 14. This dome is formed at the top of a heating 55 drum 15, which member is disposed at one

end of the radiator and is in communication with the bottom of the radiator through a water circulating pipe 16.

The heating unit comprises the drum 15 which is substantially cylindrical in formation and is intended to receive a plurality of heating elements 17. These elements are preferably arranged in diagonal and staggered relation to each other, thus providing obstructions against which the upwardly circulating water may strike and be thoroughly distributed around the various heating elements.

Reference being had to Figs. 3 and 4, it will be seen that each of the heating elements comprises an outer cylindrical shell 18 preferably formed of thin copper and within which a core 19 is positioned. This core is molded from dielectric material, and fits within the shell. The core is substantially spool shaped, having one end 20 conforming to the closed end of the shell, and its other end 21 enlarged to provide a bolting flange by which the core is secured to the drum on the heater. The shell 18 is formed with an outwardly flaring flange 22, which is disposed between the bolting flange and the outer face of the heater, thus making it possible to rigidly secure the assembled heating unit in a detachable position 85 relative to the drum.

The body portion of the core between the heads is of reduced diameter and at its opposite ends is formed with a plurality of radially extending fingers 23. These fingers are inclined toward the ends of the head and cooperate with inclined faces formed at the backs of the heads on both ends of the core to provide slots 24 into which the resistance wire of the heating unit may be positioned. The fingers upon the opposite ends of the core are staggered relative to each other so that the resistance wire may be readily wound back and forth from fingers on one end to the next succeeding fingers on the opposite end, until the entire circumference of the core has been traversed. Openings 26 are formed through the enlarged head of the core to receive the terminal ends of the resistance wire. For the purpose of ventilation an enlarged central opening 27 is formed directly through the core and also through the closed end of the shell 18. Attention is directed to the fact that this closed end of the shell projects 100

through the side wall of the heating drum upon the opposite side from that to which the bolting flange is secured.

In order to make the heater applicable for various temperatures required, the heating elements are electrically connected with a three-way switch 28, by which one or any plurality of the elements may be thrown into a circuit and the temperature of the water thus controlled. A fuse box 29 is conveniently secured to the side of the drum 15. The temperature of the water may be automatically controlled by a suitable thermostat diagrammatically indicated at 30.

In operation of the present invention the heater is assembled as shown in Fig. 1, after which suitable electrical connections are made. The heat generated by the heating elements 17 will cause an upward circulation of water to take place through the drum 15 and the pipe 13. This circulation will continue around through the pipe 16 and again through the drum. The approximate temperature of the water may be controlled by operating a desired number of the heating elements. The temperature may be further controlled automatically by the thermostat 30. In the event that an excessive heat is attained the safety valve 12 will blow off permitting the radiator to be vented. It will thus be seen that the heater here disclosed, while simple in its construction and operation, provides means whereby a heating radiator may be economically maintained at a desired temperature by readily controlled electrical means.

While I have shown the preferred form of my invention, as now known to me, it will be understood that various changes in the combination, construction, and arrangement of parts might be made by those skilled in the art, without departing from the spirit of the invention, as claimed.

Having thus described my invention, what I claim and desire to secure by Letters Patent is:

1. In an electric heating device a heating unit comprising a thin metal shell being substantially closed at one end and formed at its opposite end with an out-turned flange, a core of dielectric material mounted within said shell, said core being spool-shaped to provide heads fitting within the opposite ends of the shell, one head being enlarged to form a flange around the opened end of the shell and against which the flange of the shell may seat whereby the unit may be detachably secured in position, and an electric heating element supported on said core.

2. A core for an electric heating element formed of dielectric material and comprising a substantially spool-shaped member around the cylindrical body portion of which, and at the opposite ends thereof, a plurality of radial wire supporting arms are formed.

3. A core for an electric heating element formed of dielectric material and comprising a substantially spool-shaped member around the cylindrical body portion of which, and at the opposite ends thereof, a plurality of radial arms are formed and are disposed in staggered relation to each other at the opposite ends of the structure.

4. A core for electric heating elements, comprising a substantially spool-shaped member of dielectric material, sets of oppositely and outwardly inclined radial arms formed integral with the core near its opposite ends, and over which resistance wire may be wound.

5. A core for electric heating elements, comprising a substantially spool-shaped member of dielectric material, sets of oppositely and outwardly inclined radial arms formed integral with the core near its opposite ends and over which resistance wire may be wound, one end of said core being enlarged to form a fastening flange therefor.

6. A core for electric heating elements comprising a cylindrical member of dielectric material having enlarged heads on each end, radial outwardly extending fingers on the cylindrical member spaced from the heads and arranged in staggered relation to each other.

7. A core for electric heating elements comprising a cylindrical member of dielectric material having enlarged heads on each end, a casing for the core having a rounded end, one of the said heads fitting within and conforming to the said rounded ends of the casing.

8. A core for electric heating elements comprising a cylindrical member, radial outwardly extending fingers on the cylindrical member arranged in staggered relation to each other.

9. A core for electric heating elements comprising a cylindrical member having enlarged heads on each end, radial fingers carried by the cylindrical member and arranged in staggered relation to each other, one of the said enlarged heads having openings therein to receive a resistance element.

10. A core for electric heating elements comprising a spool-shaped member, around the cylindrical portion of which a plurality of radial supporting arms are formed, the said core having a ventilating passage therethrough.

11. A heating device comprising a drum, a plurality of heating elements in the drum each heating element comprising a spool-shaped core having a ventilating passage therein, a casing extending through the drum and receiving the core, the said casing having an opening therein registering with the ventilating passage in the core.
